UNITED STATES PATENT OFFICE.

FREDRICH J. RODE, OF CHICAGO, ILLINOIS, ASSIGNOR TO MARQUETTE TOOL & MANUFACTURING CO., OF CHICAGO, ILLINOIS, A CORPORATION OF ILLINOIS.

DIE CUSHION.

Application filed June 10, 1926. Serial No. 114,908.

This invention relates to improvements in die cushions for sheet metal drawing presses, and one of the objects of the invention is to provide improved means for mounting the cushion and pressure pad upon the bed of a press whereby the pad will be provided with long or extended bearings and whereby the pad will be guided in its movement and will be prevented from tipping under the action 5 of the draw ring pins thereon, whether the pins are placed to one side of the center or not, or whether a greater number of pins is placed on one side of the pressure pad than on another side thereof.

10 A further object is to provide improved means for extending or building up the top surface of the pressure pad to a required or desired distance above the bed of the press.

To the attainment of these ends and the accomplishment of other new and useful objects as will appear, the invention consists in the features of novelty in substantially the construction, combination and arrangement 20 of the several parts hereinafter more fully described and claimed and shown in the accompanying drawings illustrating this invention, and in which—

25 Figure 1 is a front elevation of a sheet metal drawing press having a die cushion applied thereto in accordance with the principles of this invention.

30 Figure 2 is a horizontal sectional view taken on line 2—2, Figure 3.

35 Figure 3 is a vertical sectional view of the lower part of the press showing the parts in one position.

Figure 4 is a view similar to Figure 3 showing the parts in another position.

40 Figure 5 is a horizontal sectional view taken on line 5—5, Figure 3.

Figure 6 is a horizontal sectional view taken on line 6—6, Figure 3.

45 Referring more particularly to the drawings the numeral 10 designates generally the bed plate of the press which may be supported in a manner common in machines of this character.

50 A crank shaft 11 is supported by the framework 12 of the machine which is rotated in any suitable manner, and a reciprocating ram 13 is connected with the crank shaft by means of suitable links 14.

55 The links 14 are adjustable by means of adjusting devices 15 whereby the extent of movement of the ram 13 may be varied.

In the present form of the invention a double press is shown and as the construction and operation of both portions thereof is the same the specific description of one of these portions or sections will apply equally as well to them both.

Connected with the ram 13 is a die member 14.

The bed 10 of the press is provided with an opening 16 therethrough and projections 17 extend inwardly from the wall of the bed plate and are disposed preferably adjacent the top portion of the bed plate but below the upper surface thereof. Any number of these projections 17 may be employed but 7 preferably four of them are used.

Passing through each of the projections 17 is a rod or hanger member 18, the upper extremity of each of which is threaded to receive a nut or collar 19, the latter resting upon the projections 17 to form a support for suspending the rods or hangers 18 therefrom.

These rods 18 may be of any desired length and depend below the bed plate preferably into a pit 20, and adjustably supported by the lower ends of these rods or hangers preferably by means of nuts or collars 21, is a supporting plate 22 upon which a fluid pressure cushion embodying a cylinder 23 rests.

Within the cylinder is arranged a reciprocable piston (not shown) to which is connected a piston rod 24 that extends through the top of the cushion and is connected with the pressure pad 25. The pad 25 is provided with an opening into which the extremity of the piston rod 24 telescopes and the pad and piston rod are secured together preferably by means of a collar 26 which is seated in a reduced portion 27 in the piston rod 24. A cap 28 encompasses the piston rod and is connected with the pressure pad 25 in any suitable manner so that the pad 25 and piston rod 24 will reciprocate together. When pressure is admitted into the cylinder 23 through a pressure supply pipe 29 leading from a suitable source of fluid pressure supply (not shown) the piston is elevated causing the pad 25 to be raised. When pressure is exerted upon the pad 25 to lower the piston the fluid pressure will flow out of the pipe 29.

The pad 25 is provided with extended sleeves or bearings 30 through which the

2 rods 18 respectively pass. These sleeves or bearings 30 are of a considerable length so as to form extended bearings for guiding the pad 25 in its movement and these sleeves 5 also operate to prevent the pad from tilting or tipping under the action of the draw ring pins when pressure is exerted thereupon whether the pins exert a uniform pressure 10 on one or both sides of the pad and regardless of the number of pins arranged on opposite sides of the pad.

It is sometimes desirable to build up the pressure pad so as to extend the same for a considerable distance above the bed plate 10 15 of the press and especially when it is desired to perform on a long stroke or deep draw press an operation requiring a shorter stroke of the die carried by the ram of the press.

In order to accomplish this result the ram 20 13 is adapted to be adjusted with respect to the crank shaft 11 through the medium of the adjusting devices 15 and in order to compensate this adjustment the top surface of the pressure pad upon which the draw 25 ring pins operate, is extended by means of extension stools or members 31, any number of which may be employed according to the height to which it is desired to extend the 30 surface of the pad.

These stools are adapted to be connected together against relative lateral displacement in any suitable manner such as by means of locking pins 32 adapted to be threaded into one face of one of the stools 35 and to enter a co-operating or receiving recess in the proximate face of the next adjacent stool or member 31.

In the present form of the invention three 40 of these extension stools or members are provided and the pins 33 which support the draw ring or blank holding member 34 engage and rest upon the upper surface of the uppermost stool or member 31.

A supporting member 35 is provided, 45 which is preferably of an annular construction, any number of which may be provided, here shown as two, are superposed upon each other, the lowermost member resting upon the bed plate 10. These members 50 35 encompass the extension stools or members 31 and serve as a support for a bolster plate 36, the latter being secured in position in any suitable manner.

The pins 33 pass loosely through the bolster plate 36 and engage the uppermost extension stool or section 31, and supported by the bolster plate and secured thereto in any suitable manner is a die 37 with which the die 14 co-operates.

In operation the material to be formed is placed upon the top of the die 37 and the draw ring 34 when the parts are in the position shown in Figure 3, fluid pressure being admitted into the cylinder 23 through the pipe 29.

As the ram descends the die 14 will cooperate with the draw ring 34 to clamp the material therebetween, and a further lowering of the die 14 will cause the material to be shaped over the die 37, as shown in Figure 4. During this shaping movement the draw ring 34 will be lowered causing the pins 33 to force the extension stools or sections 31 and the pressure pad 25 downwardly against the fluid pressure in the cylinder 23.

When the ram 13 rises, carrying with it the die 14 the pressure in the cylinder 23 will raise the pressure pad 25, the extension stools or members 31, and the draw ring 34.

With this improved construction it will be manifest that there is provided a means which will be of a rigid construction embodying the guide rods 18 and a pressure pad having long or extended bearings 85 guided upon these rods in such a manner that the draw ring or die pins 33 may be placed in any position upon the surface of the pressure pad or of the extension stools or sections, if the latter are employed, 90 either in the center or off to one side of the center, or a greater number of pins may exert their pressure upon one side than those present upon the other side of the pad or extension without the danger or serious effect of tilting the pressure pad, but under all conditions the pressure pad will be maintained straight or in a proper position and will be guided in its movements.

Obviously the lateral faces of the extension stools or members 31 will be shaped to 100 permit the proper reciprocation thereof.

Furthermore, with this improvement it will be manifest that provisions have been made whereby the top surface of the pressure pad may be extended so that the pad 105 will be disposed at any desired distance above the bed of the press.

While the preferred form of the invention has been herein shown and described, 110 it is to be understood that various changes may be made in the details of construction and in the combination and arrangement of the several parts, within the scope of the claims, without departing from the spirit 115 of this invention.

What is claimed as new is:—

1. In combination, a draw press embodying a plunger, a work holding element co-operating therewith, a cushion for the work holding element, means for supporting the cushion from the press, and a pressure pad interposed between the cushion and the work holding element, there being extended guiding portions carried by the said pad for 120 maintaining the pad against tilting movement.

2. In combination, a draw press embodying a plunger, a work holding element co-operating therewith, a cushion for the work 125 130

- holding element, means for supporting the cushion from the press and embodying extended hanger members, and a pressure pad interposed between the cushion and work holding element, there being extended bearings connected with the said pad through which the said hanger members pass for maintaining the pad against a tilting movement.
- 6 3. In combination, a draw press embodying a plunger, a work holding element co-operating therewith, a cushion for the work holding element, hanger members for suspending the cushion from the press, a pressure pad disposed between the cushion and work holding element, there being extended bearings carried by the pad and through which the said hanger members pass, for guiding and maintaining the said pad against a tilting movement, said cushion including a piston, and means connecting the piston to the said pad.
- 10 4. In combination, a draw press embodying a plunger, a work holding element co-operating therewith, a cushion for the work holding element and spaced therebelow, means for suspending the cushion from the press, a pressure pad movable upon the last recited means and interposed between the cushion and work holding element, and a plurality of extension members mounted upon the top surface of the said pad for building up the top surface of the pad.
- 14 5. In combination a plunger, a work holding element co-operating therewith, a cushion for the work holding element and spaced therebelow, a pressure pad disposed between the said cushion and the work holding element, an extension member mounted upon the top surface of the said pad for building up the said surface, and pin like members supporting the said work holding element and contacting with the top surface of the said extension member.
- 18 6. In combination a plunger, a work holding element co-operating therewith, a cushion for the work holding element and spaced therebelow, a pressure pad disposed between the work holding element and the said cushion, an extension member removably supported by the top surface of the said
- pad for building up the said surface, and means whereby pressure applied to the said work holding element will be exerted upon the said extension member. 55
7. In combination a plunger, a work holding element co-operating therewith, a cushion for the work holding element and spaced therebelow, a pressure pad disposed between the work holding element and the said cushion, an extension member removably supported by the top surface of the said pad for building up the said surface, means whereby pressure applied to the said work holding element will be exerted upon the said extension member, and means forming extended bearing surfaces for the pad to maintain the pad against a tilting movement. 60
8. In combination a plunger, a work holding element co-operating therewith, a cushion for the said element and spaced therebelow, a plurality of extension members superposed upon the top surface of the pad for building up the said surface, interengaging means between the respective members and the said pad for positioning them with respect to each other and for maintaining them in such position, and means whereby pressure created upon the work holding element will be exerted upon the said extension members and pad. 70
9. In combination, a draw press embodying a plunger, a work holding element co-operating therewith, a pressure pad for the said element and spaced therebelow, a plurality of extension members superposed upon the top surface of the pad for building up said surface, interengaging means between the respective members and the said pad for positioning them with respect to each other and for maintaining them in such position, means whereby pressure created upon the work holding element will be exerted upon the said extension members and pad, and an independent element encompassing the said extension members and supported by the press. 80
- In testimony whereof I have signed my name to this specification on this 28th day 100 of May, A. D. 1926.
- FREDRICH J. RODE.
